UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

LAMP-SOCKET.

1,239,317.

Specification of Letters Patent. Patented Sept. 4, 1917.

Application filed April 6, 1916. Serial No. 89,389.

To all whom it may concern:

Be it known that I, GEORGE B. THOMAS, a citizen of the United States of America, and residing at Bridgeport, in the county of 5 Fairfield and State of Connecticut, have invented a certain new and Improved Lamp-Socket, of which the following is a specification.

My invention relates to lamp sockets and 10 particularly to sockets of the Edi-Swan type, the object of my invention being to provide an improved construction of the socket casing and contact connections as will be more fully pointed out in the following 15 specification and shown in the accompanying drawings in which—

Figure 1 is a side elevation of a socket in which my invention is embodied, portion of the casing being broken away;

Fig. 2 is a vertical section on the line 2—2, Fig. 9;

Fig. 3 is a perspective of one portion of a casing element;

Fig. 4 is a side elevation of the insulating 25 socket body with the shell removed;

Fig. 5 is a similar view at right angles thereto;

Fig. 6 is an inverted plan of the end button of the receptacle;

Fig. 7 is a dropped perspective of the terminal button of the receptacle body and associated parts;

Fig. 8 is a section on the line 8—8, Fig. 4; and

Fig. 9 is a cross section on the line 9—9, Fig. 2.

In the majority of sockets of the Edi-Swan type it is customary to provide contact pins to engage the contacts of the lamp, 40 these pins being spring-supported and the springs serving also as conductors of the current leading to the terminals. This construction is disadvantageous since it not infrequently happens that an imperfectly adjusted lamp or attachment plug or like fitting causes arcing within the lamp socket with the result that the spring conductors become highly heated and consequently lose their temper.

According to the present invention the receptacle lamp contacts are spring-supported, but the springs are non-current carrying, with the result that even in case of short-

circuiting the springs carry no current and are consequently in no danger of becoming 55 heated to a temperature sufficiently high to injure their temper.

A second feature to which the present invention relates is the socket shell, the object of my invention in this case being to secure the advantages of a snap shell fastening with a construction adapted for the reception of the Edi-Swan type of lamp and also to provide means on the shell for holding a shade.

Referring to the drawings, the socket body is here shown comprising a pair of insulating buttons 10 and 11 held together by a pair of standards 12 and 13 (Fig. 2) which serve at the same time as bases for 70 the wire terminal binding screws 14 and 15. The wires may be led to the terminals through a strain relief button 16 which may be of any desired type, the bared ends of the wires being clamped as usual beneath the 75 binding screws 14 and 15. The lamp terminals are formed as studs 17 and 18 projecting slightly beyond the outer face of a floating button 19 of insulating material. These studs 17 and 18 are preferably formed from 80 rivets which pass through the button 19 and secure on its inner face two spring contact forks 20 and 21, the bases of which are seated in recesses. In one leg of each fork a slot 22, 23, is formed to receive a stud, 24, 25, 85 struck from plates 26, 27, which are fastened to the outer face of the button 11 of the socket body. The plate 26 is secured in position by the screw 28 which also engages the 90 foot of the standard 13. Consequently the 95 wire connected to the standard 13 by the binding screw 15 is electrically connected at all times with the lamp-receiving terminal stud 18. The other plate 27 is secured by screw 28^a to the frame 29 of a switch block 95 30 and is in electrical connection therewith.

In the position of the switch block 30, shown in Fig. 2, it contacts at its upper end with a strap 31 by the screw 32 engaging the top of the standard 12 to which the other 100 leading-in wire is secured by the binding screw 14. The circuit to the lamp-receiving terminal stud 17 may therefore be completed or broken according to the position of the switch block 30 which is controlled in well 105 known manner by the thumb key 33.

Between the button 19 and the button 11 are arranged coil springs 34 and 35 which may be engaged in position by seating them in appropriate wells formed in adjacent 5 faces of the buttons. These springs serve to constantly force the button 19 outward. When a lamp is inserted however, its contacts bear upon the studs 17 and 18 and press the button 19 inward toward the button 11, thus compressing the springs 34, 35. During this movement the spring contact forks 20 and 21 move upward on the plates 26 and 27, in wiping contact therewith, thus insuring a good electrical connection from 15 the wire terminals to the studs 17 and 18.

The casing as here shown comprises a cap 36 having a skirt 37 which telescopically sleeves over the upper end of the shell 38. These parts are provided with suitable 20 latching means 39 and 40, to prevent end-wise separation and relative rotation of the parts, after the fashion of the Goodridge Patent No. 958,626. At its lower end the shell 38 is provided with an inwardly projecting ledge 41. Resting upon this ledge is the outwardly extending shoulder 42 of the lamp-supporting sleeve 43. The outer end of the latter is recessed to afford the usual bayonet slot connection 44 for the lateral 25 studs on the lamp base (not shown). This sleeve 43 is preferably provided with an exterior threaded area 45 on which works a milled ring 46 which serves to clamp the neck of a lamp shade 47 against the bottom 30 of the ledge 41 of the casing shell 38.

This ledge 41 also supports the insulating socket body which is shouldered at 48 for this purpose. Opening below this shoulder are a pair of bays 49 and 50 into which take 40 a pair of tongues 51 and 52 stamped inward from the sleeve 43. Inasmuch as the socket body is held against rotation by the engagement of the stem of the switch key 33 with its slot in the casing shell 38, the sleeve 43 is held against rotation through its engagement with these bays 49 and 50 in the outer 45 face of the button 11. Corresponding channels 53, 54, are formed in the floating button 19 to permit the latter to be passed into the sleeve 43 beyond the straps 51 and 52.

It is obvious that the sliding connection between the parts 26 and 27 and 20, 21, may be variously modified to obtain the same relatively displaceable electrical connection and that these parts themselves may be modified in shape without departing from the scope of my invention. The arrangement of the springs 34 and 35 may also be variously altered. It is unnecessary of course to provide the threaded area 45 on the sleeve 43 if it is not desired to secure a shade to the lamp, and various other shade supporting means may be provided without departing from what I claim as my invention.

I claim as my invention:—

1. An electric lamp socket of the Edi-Swan type having an insulating body, wire terminals thereon, a floating insulating button at the lamp-receiving end of the socket, 70 lamp-engaging contacts thereon, spring means tending to force said button outward, and sliding brush means, affording constant electrical connection between said contacts and wire terminals, irrespective of 75 the position of the floating button.

2. An electric lamp socket of the Edi-Swan type having an insulating body, wire terminals thereon, a floating insulating button at the lamp-receiving end of the socket, 80 lamp-engaging contacts thereon, insulating spring means tending to force said button outward, and sliding brush means, affording constant electrical connection between said contacts and wire terminals, irrespective of 85 the position of the floating button.

3. An electric lamp socket of the Edi-Swan type having an insulating body, wire terminals thereon, a floating insulating button at the lamp-receiving end of the socket, 90 lamp-engaging contacts thereon, spring means tending to force said button outward, and slidably connected conductors for constantly electrically connecting said contacts and wire terminals. 95

4. An electric lamp socket of the Edi-Swan type having an insulating body, wire terminals thereon, a floating insulating button at the lamp-receiving end of the socket, lamp-engaging contacts thereon, spring 100 means tending to force said button outward, and slidably connected conductors for constantly electrically connecting said contacts and wire terminals, together with stop means associated with said conductors for 105 limiting the outward displacement of the button by said spring means.

5. An electric lamp socket of the Edi-Swan type having an insulating body, wire terminals thereon, a floating insulating button at the lamp-receiving end of the socket, lamp-engaging contacts thereon, spring means tending to force said button outward, and means for electrically connecting said contacts and wire terminals, said means 110 comprising a pair of spring forks and a pair of coöperating blades, one pair being electrically connected to the wire terminals and the other pair to the lamp-engaging contacts. 115

6. An electric lamp socket of the Edi-Swan type having an insulating body, wire terminals thereon, a floating insulating button at the lamp-receiving end of the socket, lamp-engaging contacts thereon, spring 125 means tending to force said button outward, and means for electrically connecting said contacts and wire terminals, said means comprising a pair of spring forks and a pair of coöperating blades, one pair being electric- 130

cally connected to the wire terminals and the other pair to the lamp-engaging contacts, said spring forks being slotted and the blades having studs working in said slots to limit the extent of separation of said insulating body and button.

In testimony whereof I have signed my

name to this specification, in the presence of two subscribing witnesses.

GEORGE B. THOMAS.
